UNITED STATES PATENT OFFICE.

JOHN PLAYER, OF DUNKIRK, NEW YORK, ASSIGNOR TO THE BROOKS LOCOMOTIVE WORKS, OF SAME PLACE.

LOCOMOTIVE DRAFT APPLIANCE.

SPECIFICATION forming part of Letters Patent No. 673,726, dated May 7, 1901.

Application filed October 9, 1900. Serial No. 32,548. (No model.)

To all whom it may concern:

Be it known that I, JOHN PLAYER, of Dunkirk, in the county of Chautauqua and State of New York, have invented a certain new and useful Improvement in Locomotive Draft Appliances, of which improvement the following is a specification.

The object of my invention is to provide a draft appliance for locomotive or other engines in which the draft upon the fire is created by the utilization of the exhaust-steam from the cylinders, by the employment of which a greater and more uniform draft may be maintained and the back pressure in the cylinders be reduced relatively to constructions heretofore known or proposed.

The improvement claimed is hereinafter fully set forth.

Locomotive draft appliances known in practice prior to my invention have ordinarily comprised an exhaust-pipe communicating with the cylinder exhaust-passages and having a single central opening or two adjoining openings for the escape of exhaust-steam, said opening, or each opening when two are used, being provided with a contracted nozzle, bushing, or cap of diameter and transverse area designed to be such as would cause the exhaust-steam to properly fill the stack and produce sufficient vacuum in the smoke-box to maintain the necessary draft upon the fire, draft, lift, or petticoat pipes for the entrainment of the gases of combustion being in many cases interposed between the exhaust-nozzles and the base of the stack for the purpose of increasing and equalizing the draft. In some instances exhaust-pipes having annular nozzles have been employed; but in all such cases, so far as my knowledge and information extend, either the exhaust-discharge opening from one cylinder has been located centrally and that of the other annularly or where the exhaust-passages from both cylinders unite in a common annular discharge-nozzle the opening for the admission of the gases to fill the vacuum formed inside the annular nozzle has been located at the lower part of the exhaust-pipe and below the spark-arrester, thereby presenting two points of draft in the smoke-box and neces-

sitating an additional spark-arresting appliance to cover the lower openings in the exhaust-pipe. Moreover, by reason of the disadvantageous location of said openings it has been found in practice that the discharge area of the exhaust-nozzle cannot be materially increased and a sufficient draft upon the fire be maintained, and, further, that exhaust-pipes of this character rapidly choke up in the steam-discharge opening and cut out by the abrasion of the cinders in the central opening.

The leading and essential feature of my invention consists in the combination, with a smoke-box, of an exhaust-pipe having an annular nozzle of large area for the escape of the exhaust-steam and provided with an internal passage for the entrainment of a portion of the gases of combustion of sufficient area to enable the entrained gases to partially destroy the vacuum created in the interior of the annular column of escaping steam, said gases being admitted through openings located above a spark-arrester, so that the effective point for the creation of vacuum may be properly centralized in the smoke-box. The intensity of the vacuum is thereby augmented with a materially lower velocity of the escaping steam, and an increase in the discharge area of the exhaust-nozzle of from thirty to fifty per cent. has been found to be satisfactorily attainable in actual practice.

In the accompanying drawings, Figure 1 is a vertical longitudinal central section through the smoke-box and forward portion of the waist of a locomotive-boiler, illustrating an application of my invention; Fig. 2, a vertical transverse section through the smoke-box; Fig. 3, a side view, partly in elevation and partly in section, of the exhaust-pipe; Fig. 4, a vertical transverse section through the same; Figs. 5 and 6, horizontal sections at the lines *a a* and *b b*, respectively, of Fig. 4; and Fig. 7, a view in elevation of the exhaust-tip and upper portion of the exhaust-pipe as seen diagonally.

My invention is herein exemplified as applied in connection with a locomotive-boiler of the type now standard on railroads, in

which the shell or waist 1 is provided with a plurality of tubes 2, which are secured at their front ends to a tube-sheet 3 and through which the gases of combustion pass from the 5 fire-box to the smoke-box 4, which is secured at its rear end to the front ring of the shell 1 and at its bottom to the cylinder-saddles 5. The forward end of the smoke-box is closed by a metal front 6, having a central door 7, 10 and it is provided at top with a stack 8, to which in large locomotives having comparatively short stacks a downward extension 9, having an adjustable cone 10 at its lower end and serving as a draft or lift pipe, may be 15 connected, as herein shown.

In the practice of my invention I provide an exhaust-pipe 12, which is connected at its lower end to the cylinder-saddles 5 and communicates with the exhaust-passages 13 there- 20 of, a vertical bridge 14 extending upwardly for a proper distance in the exhaust-pipe to separate the currents of steam from said pas- 25 sages, as in ordinary practice. The interior of the exhaust-pipe is for the major portion of its height substantially unbroken or un- 30 obstructed, (the small blower-pipe herein- after described being the only member which extends into it,) so as to present nearly to its top a passage for the traverse of exhaust- 35 steam which is of the full width of its bore. The shell or wall of the exhaust-pipe is double at and for some distance below its top—that is to say, is composed of an inner and an outer body of metal. The inner body sur- 40 rounds a central passage 15 for the discharge of gases which are entrained through lateral inlet-passages 16, adjacent to the top of the exhaust-pipe, and an annular cap or tip 17, of metal, is secured removably by bolts 18 45 and nuts 19 to lugs on the outer body, an annular exhaust-steam-discharge opening 20, which constitutes the exit of the exhaust- pipe, being presented between the inner body of metal and the cap or tip 17. It will be 50 obvious that by employing caps or tips of different inward inclination or curvature, re- spectively, the area of the exhaust-discharge opening 20 may be increased or diminished as may be found necessary or desirable for 55 use with different qualities of fuel or under different conditions of service of the engine on which the appliance is used. The inlet- 60 passages 16 are located above the spark-arrester—that is to say, on the side of the net- 65 ting thereof which is farther from the tubes— both for the purpose of effecting the entrainment of gases at a proper level and to prevent the discharge of solid particles before passing through the netting of the spark-ar- 70 rester. Two of these passages are shown in this instance; but one, three, or more may be employed, if preferred, the number not being material. For convenience of construction the upper portion of the exhaust-pipe may, 75 if desired, be cast separately from the lower portion and be connected thereto by bolts.

The blower-pipe 21 is preferably inserted through the shell of the exhaust-pipe, at one side thereof, and is provided with an upward extension 22, the discharge-opening of which 70 is concentric with the gas-discharge passage 15, so that entrainment of gases and consequent augmentation of draft may be effected when steam is discharged through the blower- pipe. If preferred, a passage may be cored 75 in the casting for connection with the blower, or it may be caused to discharge in small jets disposed around the central passage 15, or it may be unconnected with the exhaust- pipe and applied externally in the ordinary 80 manner.

The spark-arresting appliance employed does not in and of itself form part of my present invention, and various constructions known to those skilled in the art will be found 85 to be suitably applicable in connection therewith. In the instance exemplified the spark- 90 arrester comprises an inclined deflecting-plate 23, which extends across the smoke-box in front of the tube-sheet 3, to which it is connected above the upper row of tubes, and which is downwardly prolonged by an adjustable perforated plate or apron 24. The upper and lower portions of the smoke-box are separated by inclined front, rear, and side sheets 95 of wire-netting or perforated plate 25, 26, and 27, the lower sides of which are secured to the exhaust-pipe below the inlet-passages 16. The front sheet is provided with a suitable man- 100 hole, which is covered by a removable frame 105 28, inclosing a sheet of netting or perforated plate, and is connected at its upper side to an unperforated vertical plate 29, extending to the top of the smoke-box. The upper side of the rear sheet 26 is connected to the deflect- 110 ing-plate 23, and the upper sides of the side sheets 27 are connected to inclined unperforated plates 30, the upper sides of which are in turn secured to the smoke-box. The side plates 30 are provided for the purpose of cen- 115 tralizing the discharge area through the spark- arrester and creating a more uniform draft. Lugs or flanges 31 on the exhaust-pipe, below the inlet-passages 16, are provided for the at- tachment thereto of the sheets of netting or 120 perforated plate.

It will be seen that my invention is simple and inexpensive in construction and readily adaptable without change in or addition to other members in locomotive-boilers of the ordinary construction. The relation of the steam and gas discharge passages of the exhaust-pipe one to the other and to the spark- 125 arresting appliance is such that it is impossible for any cinders or unconsumed fuel which may be drawn through the boiler-tubes to enter the gas-discharge passage until after passing through the netting or other separating medium of the spark-arrester, and the location of the gas-inlets adjacent to the exhaust- 130 cap enables the draft-inducing action of the exhaust-steam to be exerted as nearly as may

be centrally in the smoke-box, where it is most effective in the production of vacuum under a comparatively free discharge.

My improvement, while herein shown as more particularly designed for application in locomotive-boilers, is equally adaptable to use in any other type of boiler in which the exhaust-steam is employed to maintain the draft upon the fire. It has been applied with entirely satisfactory results as to free steaming and economy upon several different railroads, and the material reduction of back pressure due to its use will be manifest from the fact that in the instances referred to the exhaust-steam-discharge area of the nozzle has been made forty per cent or more in excess of that used in exhaust-pipes of the ordinary construction.

I claim as my invention and desire to set out by Letters Patent—

1. The combination, with a boiler smoke-box, of an exhaust-pipe having a central passage for the discharge of gases, inlet-passages leading thereinto for the entrainment of gases, and an annular steam-discharge passage surrounding the gas-discharge passage, and a spark-arrester extending from the walls of the smoke-box to the exhaust-pipe, below the inlet-passages thereof, and intercepting the traverse of products of combustion into the gas-discharge passage.

2. The combination, with a boiler smoke-box, of an exhaust-pipe having a central passage for the discharge of gases, inlet-passages leading thereinto for the entrainment of gases, and an annular steam-discharge passage surrounding the gas-discharge passage, a cap or tip secured removably to the top of the exhaust-pipe and forming the upper outer wall of the steam-discharge passage, and a spark-arrester extending from the walls of the smoke-box to the exhaust-pipe, below the inlet-passages thereof, and intercepting the traverse of products of combustion into the gas-discharge passage.

3. The combination, with a boiler smoke-box, of an exhaust-pipe having concentric inner and outer walls at and adjoining its top, the space between said walls being open at top and communicating with the interior of the exhaust-pipe, and the inner wall surrounding a central open-topped gas-discharge passage, and inlet-passages leading into said gas-discharge passage, and a spark-arrester extending from the walls of the smoke-box to the exhaust-pipe, below the inlet-passages

thereof, and intercepting the traverse of products of combustion into the gas-discharge passage.

4. The combination, with a boiler smoke-box, of an exhaust-pipe having a central passage for the discharge of gases, inlet-passages leading thereinto for the entrainment of gases, and an annular steam-discharge passage surrounding the gas-discharge passage, an inwardly curved or inclined cap or tip secured removably to the top of the exhaust-pipe and forming the upper outer wall of the steam-discharge passage, and a spark-arrester extending from the walls of the smoke-box to the exhaust-pipe, below the inlet-passages thereof, and intercepting the traverse of products of combustion into the gas-discharge passage.

5. The combination, with a boiler smoke-box, of an exhaust-pipe having a central passage for the discharge of gases, inlet-passages leading thereinto for the entrainment of gases, and an annular steam-discharge passage surrounding the gas-discharge passage, a blower-pipe leading into the gas-discharge passage, and having an open end concentric therewith, and a spark-arrester extending from the walls of the smoke-box to the exhaust-pipe, below the inlet-passages thereof, and intercepting the traverse of products of combustion into the gas-discharge passage.

6. In a draft-inducing exhaust-pipe, the combination of an outer shell or wall inclosing a passage for the traverse of exhaust-steam, which passage is substantially the entire bore of the shell for the major portion of its height, an inner shell or wall located at and adjoining the upper end of the outer shell and forming the outer boundary of a central gas-discharge passage and the inner boundary of a concentric annular exhaust-steam-discharge passage, an annular cap or tip secured removably to the outer shell and forming the upper outer wall of the steam-discharge passage, inlet-passages formed by and between the inner and outer shells and leading into the gas-discharge passage, adjacent to the top of the exhaust-pipe, and lugs or flanges fixed to the outer shell, below said inlet-passages, for connection with a spark-arrester.

JOHN PLAYER.
